Inventor:

Theodor W. Mahler.

THEODORE W. MAHLER, OF ROME, NEW YORK.

Letters Patent No. 84,292, dated November 24, 1868; antedated November 9, 1868.

IMPROVEMENT IN WATER-WHEELS.

The Schedule referred to in these Letters Patent and making part of the same.

To all whom it may concern:

Be it known that I, THEODORE W. MAHLER, of Rome, Oneida county, New York, have invented a new and improved Water-Wheel.

My improved wheel is a horizontal central-discharge wheel. The water passes on to the wheel by a double scroll, and there is a separate gate at the front of each guide, which gates move radially, or in the direction of the radii of the wheel, in opening and closing, and are moved simultaneously, by raising and lowering a lever.

The brace is divided, or in two parts, to admit of the wheel being put together or taken apart readily. The lower hub of the wheel is raised above the lower rim, by means of a curved arm, to allow the end of the shaft to be enlarged, when additional strength or bearing is required, without raising the wheel, and thus losing head, and the gates have each a spring-extension.

And I do hereby declare that the following is a full, clear, and exact description of the said invention, and of the mode of operation of the same, reference being had to the annexed drawings, making a part of this specification, in which—

Figure 1 is a plan of the water-wheel;
Figure 2 is a sectional view thereof;
Figure 3 represents the divided brace;
Figure 4 is a perspective view of the guide and gate; and

Figure 5, one of the gates.
A is the case.
A¹ A² are the scrolls.
A², the point where they meet.
B, the wheel.
B¹, the lower rim.
B², the curved arm.
C, the shaft.
C¹, enlarged end of shaft.
C², the step.
D, the brace.
D¹ and D², the separate parts thereof.
D³, screws for holding it together.
D⁴, bearings for shaft.
D⁵, set-screws.
E, the guides.
E¹, short curved end.
E², a slot therein.
F, the gates.
F¹, a hole therein.
F², the extension part.
F³, the spring.
F⁴, pins and slots.
G, rods or shafts.
G¹, arm or lever thereon.
G², upper arm or lever.
G³, cap.
H, a ring or thimble.
I, arms.
K, lever.
K¹, a joint.

The case A is in the form of a double scroll, having one scroll, A¹, on each side of the wheel, with the narrow ends of the scrolls A² united at the back of the wheel, as seen in fig. 1, by means of which arrangement all the buckets are kept filled, and there is less waste of power, by reason of the friction of the water, than where there is but one scroll winding around the entire wheel, as in ordinary cases.

The double scroll, as described, has advantages over the ordinary penstock, as it may be attached to the end or side of the flume, and may be readily removed for repairs, or the water shut off from the wheel, as well as the buckets. If set in the penstock, the whole would have to be taken apart for repairs, and the water could not be shut off from the wheel. Nor would it perform equally well if the wheel were seated centrally in the scrolls, as the buckets on the back side would not be equally filled.

The wheel B has the lower rim, B¹, connected to the shaft at a point higher than said rim, by means of a curved arm, B². The purpose of this is to allow the end of the shaft C to be enlarged at C¹, where it is required to support heavy weight, as is often the case where long vertical shafting is necessary. But for this curved arm, which allows a sufficient space between the step C¹ and the hub of the wheel to enlarge the shaft, the whole wheel would have to be raised above the step, and thus cause a loss of head.

The brace D is divided through the bearing part into two parts, D¹ and D², which are held together by the screws D³ D⁴, by means of which arrangement the wheel can more readily be taken apart and put together.

D⁴ are bearings in the brace, and D⁵ are screws for regulating the same.

The guides may be two or more, each of which has a short outward curve, E¹, at its outer end, so turned that when the guide is in place, the front face of such curve is in the direction of the radius of the wheel. In the edge of E¹ is a slot or notch, E². In front of E¹ is placed the gate F, the inner end of which rests against the rear end of the preceding guide. It stands in the direction of the radius of the wheel, and thus closes the passage to the wheel. The inner end of F is slotted, and has fitted therein a separate part, F², and which is pressed outward by the spring F³, but is prevented from getting out of place by the pins and slots F⁴.

By this arrangement of the parts, an obstruction of one gate will not prevent the closing of all the others.

Behind each gate is a rod or shaft, G, which has a bearing in the lower side of the case, and passes through the upper one. This rod has an arm, G¹, thereon, which extends through the slot E², and the hole F¹ in the gate, and serves as a lever to open and close the gate. On the upper end of G, above the case, is another arm, G².

The outer end of G², which is in the opposite direction to G¹, has a globular socket in connection with the plate G³, which plate is held in place by a screw.

Surrounding the lower part of the brace D, is a ring

or thimble, H , arranged to slide up and down on such brace. Connected with this ring or thimble by joints, are arms I , equal in number with the gates, the outer ends of which are formed with a ball, which fits into the socket in G^2 , and the whole, with the cap G^3 , forming a ball-and-socket joint. Over the ring or thimble H , and attached thereto by a joint, K , is a lever, K , by means of which said ring or thimble H is raised and lowered which causes the gates to open and close.

The operation is as follows:

Fig. 1 represents the gates as closed. By raising the lever K , the ring H is raised. This draws with it all the rods I , which in turn causes the end G^2 of the arms or levers G to turn inwards, and of course the arm or lever G^4 to turn outwards, which acting on the gate F , through the hole F^1 , causes each gate to slide out radially, and the water will rush in at the same moment, and fill all the buckets with equal volume. By depressing the lever K , the quantity of water may

be diminished, and by letting it fully down, it will shut off the water entirely.

If by chance an obstruction should get in any one of the gates, by means of the spring-extension, all the gates but the one obstructed may be closed, without which this could only be done in this case, or in any case where all the gates are opened and closed by one movement, by removing the obstruction.

Having thus described my invention,

What I claim therein as new, and desire to secure by Letters Patent, is—

1. The double scroll, constructed and arranged in relation to the wheel, substantially as described.
2. The extension gate $F F^2$, constructed and arranged to operate as described.

T. W. MAHLER.
